ELECTRON DISCHARGE TUBE

Filed Feb. 25, 1928

INVENTOR.
Montford Morrison

UNITED STATES PATENT OFFICE

MONTFORD MORRISON, OF CHICAGO, ILLINOIS, ASSIGNOR, BY MESNE ASSIGNMENTS, TO
WESTINGHOUSE LAMP COMPANY, A CORPORATION OF PENNSYLVANIA

ELECTRON DISCHARGE TUBE

Application filed February 25, 1928. Serial No. 256,916.

The present invention relates to luminous discharge tubes of the gaseous ionization type, such as used for illuminated advertising signs and the like. This invention is constituted of some of the elements disclosed in my co-pending application, Serial 566,961, filed June 9, 1922, and is a part thereof.

Among the objects of my invention are; to provide a method of exhausting and filling 10 luminous discharge tubes such as to eliminate trapped foreign gases which are responsible for variation in intensity as well as variation in color in luminous discharge tubes; to provide means for stabilizing the 15 gas pressure in these tubes, as well as stabilizing the mixture of the gas content of these tubes; to provide a novel electrode disclosed in my above-mentioned application, which electrode greatly improves the stable 20 operation of the tube and prevents the formation of a focusing cathode ray stream which is responsible for many of the punctures found in common practice, and also to provide a protection at the point of emergence 25 of the lead-in wires into the vacuum chamber such as to prevent deterioration of the lead-in wire and leakage of gas at this point.

Fig. 1 represents a completed tube showing an embodiment of my invention after the 30 tube has been sealed off of the apparatus used in connection with producing it. Fig. 2 is a complete embodiment of my invention showing the method of pumping the tube as well as the method of filling it, and Fig. 3 is an 35 enlarged cross-section of one of the electrodes and electrode chamber.

In the prior art, the methods of evacuating and filling luminous tubes of this class have invariably been to make one sealing-in connection to the tube and pump the tube from this sealing-in connection, as well as after the tube has been pumped to allow the gas which 40 fills the tube to enter the evacuated chamber of the structure at the same opening.

45 This, I have discovered, accounts for much of the erratic behavior of these tubes, their short life as well as for the fact that the tubes have to be seasoned by a long continued operating process which, in some cases, has to be continued for several days before the tube

will assume its normal color and operating characteristics.

I have discovered that in these methods used in the prior art, involving the above process referred to, that there is always a 55 certain amount of residual gas trapped within the tube, and it is this trapped gas that is responsible for the variation in intensity of the tube, as well as the variation in color, and this aging process, I have discovered, is 60 merely a means which tends to "get" foreign gas which is left into the tube.

In my invention I totally obviate this seasoning process by a method of filling the 65 evacuated chamber in such a way that it contains only the desired gas, and no foreign gas, hence all the difficulties experienced with the prior art processes are eliminated.

In the prior art tubes, electrodes have been 70 always employed having a multiplicity of "firing points" which either comprise sharp points or sharp edges. Cylindrical pieces have been employed with holes drilled in them producing sharp edges at the boundaries of the cylinders, wires having points 75 have been utilized, and in some cases electrodes constructed so that the sharp edges of the electrode was greatly increased.

I have discovered, as disclosed in my above 80 referred to application, that a great deal of 85 the erratic behavior in electron tubes is due to these sharp edges or points which concentrate the electrostatic field at points, causing excessive ionization where it is not desired. In the present invention, I employ the electrode 85 disclosed in my above mentioned application in such a way that the discharge is uniform around the whole surface of the electrode, eliminating all concentration of the electrostatic field and thereby obviating 90 this erratic behavior, which I have discovered is due to electrostatic field concentration.

One of the other disadvantages of the tubes in the prior art lies in the fact that in a desire to obtain an elongated chamber of small 95 cross section the total volume of the evacuated chamber has always been greatly reduced, and the watt dissipation of the tubes per unit volume of the total chamber is high, which I have discovered accounts for unduly 100

rapid changes in the gas pressure, shortening the life of the tubes. In my invention I have provided means for stabilizing the gas pressure, as well as the gas mixture in the active part of the tube, thereby quite obviously increasing the tube life.

Having described my invention in general terms, reference may now be had to the accompanying drawings.

Fig. 1, 1 is an elongated gas chamber of glass or other suitable material on to the right end of which is sealed an enlarged chamber 2 having seal-in wire 3 and an electrode 4, of a particular construction herein-after described. On the left-hand of the tube 1 is a large cylindrical chamber 5, similar to that located on the right end and containing a similar electrode 6 and seal-in wire 7. 8 is an enlarged chamber sealed on to a part of the evacuated chamber of a luminous discharge tube to increase its total volumetric content, as well as to supply gas to the luminous discharge tube when its pressure is lowered due to operation.

In Fig. 2 is shown the completed tube of Fig. 1 in process of production. Similar parts are similarly numbered. 9 is an evacuating pump connected to a piece of tubing 10, which is sealed on to the chamber of the luminous tube at 11, by which connection the entire contents of the chamber of the luminous tube may be evacuated. Tubing 10 is provided with a stop cock 34. 12 is a bottle containing a gas or vapor which is to be introduced into the luminous tube. 13, 14 and 15 are stop cocks which are used to measure the amount of gas admitted into the luminous tube, as well as to disconnect the bottle 12 from the evacuated chamber. The bottle 12 is connected to the luminous tube at an opening remotely disposed from 11 and at 35.

31 is an additional bottle containing a gas or vapor, and provided with stop cocks 32 and 36 for measuring the gas therefrom. The bottle 31 is sealed on to the tube line of the gas bottle 12 at point 33.

16 is a source of alternating electromotive force which is fed by leads 17 and 18 through switch 19 to primary 20 of step-up transformer 21, which, by means of induction to secondary 22, supplies high voltage to the electrodes 4 and 6 of the luminous tube by means of leads 23 and 24.

55 In Fig. 3, similar parts of Figs. 1 and 2 are similarly numbered. Electrode 6 of Fig. 3 presents a rounded contour at all points such as 25, 26 and 27, and the like. The lead-in wire 7 is sealed into a glass tube 28 over 60 which the electrode 6 is placed, as shown at 29. This construction shields the lead-in wire at 30 from the electric field of the discharge, and prevents its deterioration at this point, as well as preventing the concentration of field due to the small lead-in wire, in addi-

tion to which this construction greatly strengthens the supporting structure of electrode 6 such as to prevent its breaking off or being injured in transit.

As disclosed in my parent application, such an electrode prevents the concentration of electric field at or about the electrode. The local concentration of electric field in a discharge tube sets up local heating, which tends to liberate gas from the electrode, which in turn destroys the stability of the tube by changing the gas content of the discharge chamber. With this electrode under operation, the entire field adjacent uniformly glows with discharge, showing no concentration of field and no concentration of luminous intensity at or near any particular part of the electrode.

The process of evacuating and filling tubes to operate in accordance with my invention may be understood by reference to Fig. 2.

First, the stop cocks 13, 14 and 15 are turned to their off position and the evacuating pump 9 is set into operation and the gas is removed from the total chamber under evacuation by means of the pump and any other such accessory means as heating the glass envelope, heating the electrodes, and operating the tube under electrical discharge by means of transformer 21. These accessory devices are merely means for ridding the electrodes and glass parts more completely of gas than would be otherwise possible.

After chamber 1 has been sufficiently evacuated, stop-cock 34 is closed, stop cocks 13 and/or 14, depending upon the conditions, are opened, admitting some of the gas or vapor content in bottle 12 into the tube between stop cocks 13 and 15. Then stop cock 13 is turned to the off position and stop cock 15 is opened, allowing the trapped gas to flow into the chamber 1.

At this point it can be best appreciated that following the prior art method of admitting gas at the vacuum pump seal-in 11, results only in the gas admitted at 11 trapping the residual gas in the tube 1 and pushing it down usually to the opposite end of the tube in the end occupied by chamber 5, and that by no method or means may the gas thus trapped be evacuated by pump 9. By repeated processes of pumping and allowing the gas to flow in at the same opening 11, results in pockets of gas usually trapped along the tube which, under operation, very distinctly shows streaks of different colors due to the two gases being trapped at different points. By operating these tubes under long periods and going through other operations, the gas sometimes becomes sufficiently well mixed that the entire tube may, after several days' operation, have all the same color and assume a stable state of operation. However, some tubes never acquire this state and always show pockets of variation gas in the tubes.

In some cases I find it desirable to "wash" out the tube 1, by gases from bottle 31, through stop-cocks 32 and 36, before admitting gas from the bottle 12 into the tube 1.

Now by the processes which I have discovered, and that is by evacuating from one end of the tube, namely at 11, and allowing the gas to enter at the opposite end of the tube, namely 35, I can by one or more operations completely extrude all the residual gas from the left-hand end of the tube 5 to the right end of the tube 2, and finally out through the pump at 11. In some cases I utilize the stop cock 34 for cutting the pump off at times, as a matter of practicability in the process of producing the tube.

A tube produced under this process, having no foreign gases present, does not require to be seasoned and does not require any process of destroying the gas or thoroughly mixing it so as to obviate different colored gas discharge sections.

A tube thus constructed operates from the very beginning of its life with a perfectly uniform discharge throughout the entire luminous portion, and with entire absence of streaks or other related undesirable characteristics. The great time cost in trying to rid the tube of this gas is entirely eliminated.

In addition to this, the tube burns with a brilliance not attained by tubes constructed by the prior art. The tube has a long stable life because there is no concentration of electric fields at the electrodes 4 and 6. Since the discharge is perfectly uniform over these electrodes, they work at a uniform temperature and, therefore, give uniform behavior. Because the original air is entirely absent from the tube, there is substantially no oxygen present to attack the electrodes and change their surface characteristics, and, therefore, change their operating behavior. Therefore, the tube operates in a stable condition for a greater period of time than do tubes of the prior art. The non-focusing construction of my electrode, eliminates puncturing of the glass tubes due to the cathode ray stream.

After the evacuating and filling process is complete, the tube 1 is sealed off at points 11 and 35, and results in the finished tube illustrated in Fig. 1. The chamber 8 shown in Fig. 1 goes into operation when the gas pressure in the luminous tube 1 changes for any reason. This chamber 8, being of large volumetric capacity, supplies gas to the luminous tube 1 on the pressure therein dropped, thus preventing the tube from "going out" due to low gas pressure, early in its life.

It will be appreciated that chamber 8 is outside of the discharge field of the luminous tube and, therefore, the electric discharge in the said tube has no effect on the gas in chamber 8, and, therefore, any gas change encountered in tube 1 due to electric discharge therein does not affect the gas in chamber

8, and, therefore, chamber 8 always remains a reservoir of pure gas to supply the discrepancies of the luminous tube 1. In this way the pressure of tube 1 is not only stable, but the purity of this gas is maintained. 70 This also greatly adds to the stable life, as well as to the length of life of a luminous discharge tube constructed according to my invention.

In the specification and claims, the word 75 "gas" is used to mean either gas or vapor, in any or all senses of both words.

Claims:

1. A gaseous conduction discharge device comprising an enclosing envelope, an inert 80 gas filling and a plurality of electrodes, at least one of said electrodes having means to distribute the electrical discharge uniformly over the electrode surface and a sealed-in lead-in conductor constituting a support 85 for said electrode.

2. A gaseous conduction discharge device comprising an enclosing envelope, an inert gas filling and a plurality of electrodes, at least one of said electrodes having surface 90 characteristic means to cause an electrical discharge to radiate with substantial uniform intensity over its entire surface and a sealed-in lead-in conductor disposed internally of said electrode and constituting a sup- 95 port therefor.

3. A gaseous conduction discharge device comprising an enclosing envelope, an inert gas filling and a plurality of electrodes, at least one of said electrodes being substantially free of points of electric flux concentration over its entire active surface and a sealed-in lead-in conductor disposed internally of said electrode and constituting a sup- 100 port therefor.

4. A gaseous conduction discharge device comprising an enclosing envelope, an inert gas filling and a plurality of electrodes, at least one of said electrodes being substantially curvilinear over its entire active surface and provided with a sealed-in lead-in conductor disposed internally of said electrode and constituting a support therefor. 110

5. A gaseous conduction discharge device comprising an enclosing envelope, an inert 115 gas filling, a plurality of electrodes, and means to uniformly distribute the electrical discharge over the entire active surface of said electrodes provided with a sealed-in lead-in conductor disposed internally of said electrode and constituting a support therefor.

6. A gaseous conduction discharge device comprising an enclosing envelope, an inert gas filling, a plurality of electrodes, said electrodes having surface characteristic means 125 to prevent the concentration of the electrical discharge upon any one point of said electrodes provided with a sealed-in lead-in conductor disposed internally of said electrode and constituting a support therefor. 130

7. A gaseous conduction discharge device comprising an enclosing envelope, an inert gas filling, a plurality of electrodes, and means to uniformly distribute the electrical discharge over the entire active surface of said electrodes said means comprising a surface shaping of said electrodes to eliminate all points of electric flux concentration thereon provided with a sealed-in lead-in conductor disposed internally of said electrode and constituting a support therefor.
